UNITED STATES PATENT OFFICE.

JOHN RIDGE, OF NASHUA, NEW HAMPSHIRE.

METHOD OF MAKING A FILE.

1,120,973.

Specification of Letters Patent. Patented Dec. 15, 1914.

Application filed July 21, 1913. Serial No. 760,153.

To all whom it may concern:

Be it known that I, JOHN RIDGE, a citizen of the United States, residing at Nashua, county of Hillsboro, State of New Hampshire, have invented an Improvement 5 in Methods of Making Files, of which the following description, in connection with the accompanying drawing, is a specification, like characters on the drawing representing 10 like parts.

This invention relates to files and has for its object to provide a novel method of making a file which is formed on its face with a central groove to divide the surface thereof 15 into two parts on which the teeth are cut in opposite directions.

The features wherein my invention resides will be more fully hereinafter set forth and will then be pointed out in detail in the 20 appended claim.

Referring now to the drawings wherein I have illustrated some of the steps involved in the practice of my invention, Figure 1 is a perspective view of a section of the strip 25 of metal from which the file is made; Fig. 2 is a perspective view of one of the sections into which this strip is cut and from which the file is made. Fig. 3 is a perspective view of the completed file.

30 Before describing the process which constitutes my invention, I will refer briefly to the file which is produced as the result of carrying out the process. Such a file is shown in Fig. 3 and the body 1 thereof has formed in one face a groove 2 which extends 35 longitudinally of the file and preferably centrally of the body thereby to divide the face of the file into two portions 3 and 4. The teeth are cut on these two portions 3 and 40 4 in opposite directions, the teeth on each part inclining outwardly from the groove 2 toward the end of the file. The file is also provided at one end with the usual tang 5 by which a handle may be secured 45 thereto and in the file herein shown the grooves 2 and teeth formed in the portions 3 and 4 terminate a slight distance from the root of the tang. In order to make a file of 50 this nature I first provide a strip 6 of metal which has a width and thickness corresponding to the width and thickness of the

file 1 which is to be made and I then form in one face of said strip 6 a plurality of grooves 2 which are situated in line with each other, but are separated from each other. These grooves will preferably be formed in the strip 6 by a rolling process and I propose to form said grooves during the process of rolling said strip 6 from an ingot. This can readily be done by providing the final rollers of the rolling mill with 55 ribs which will operate to form grooves 2 on the strip during the last pass of the strip through the rolls.

I will preferably make the rolls of such 60 shape that each groove 2 will be approximately twice the length of the completed file. After the strip 6 has thus been produced with the grooves 2 in one face thereof said strip is cut into sections 7, each of 70 which has a groove 2 therein extending from one end nearly to the other end, as shown in Fig. 2. This can be readily accomplished by cutting the strip transversely in the places indicated by the dotted lines 8, 75 the alternate cuts extending transversely across each groove 2, midway of its length and the other cuts extending midway between the adjacent ends of the two grooves. After the grooved section 7 is thus formed 80 the ungrooved end 9 thereof is subjected to a swaging process by which the tang 5 is formed and the teeth of the file are cut in the two portions 3 and 4 on opposite sides of the groove 2. This cutting of the teeth 85 will be accomplished in the usual method and after the teeth are cut, the file will be properly tempered and is then ready for use.

By means of my process a file having a 90 central groove and the teeth on the two portions 3 and 4 cut in opposite directions can be produced as easily and economically as an ordinary file.

Having fully described my invention, 95 what I claim as new and desire to secure by Letters Patent is:

The method of making a file which consists in forming a plurality of grooves in one face of a strip of metal having the width 100 and thickness of the file to be completed, which grooves are situated in line with but

separated from each other, severing the strip into sections, each of which has a groove extending from one end thereof nearly to the other end and then forming the teeth 5 in the grooved face of the file on both sides of said groove.

In testimony whereof, I have signed my

name to this specification, in the presence of two subscribing witnesses.

JOHN RIDGE.
